Primary Examiner—Melody N. Brown

(57) **CLAIM**

The ornamental design for a fender, as shown and described.

DESCRIPTION

FIG. 1 is a front right elevated perspective view of a fender showing our new design.

FIG. 2 is a front right elevated perspective view of the fender design of FIG. 1.

FIG. 3 is a top plan view of the fender design of FIG. 1.

FIG. 4 is a right side view of the fender design of FIG. 1.

FIG. 5 is a front view of the fender design of FIG. 1.

FIG. 6 is a bottom view of the fender design of FIG. 1.

FIG. 7 is a rear view of the fender design of FIG. 1.

FIG. 8 is a left elevated perspective view of a fender design showing a second embodiment of our new design, the broken line showings of the vehicle being for illustrative purposes only, and forming no part of the claimed design.

FIG. 9 is a left elevated perspective view of the fender design of FIG. 8.

FIG. 10 is a top plan view of the fender design of FIG. 8.

FIG. 11 is a left side view of the fender design of FIG. 8.

FIG. 12 is a front view of the fender design of FIG. 8.

FIG. 13 is a bottom view of the fender design of FIG. 8; and,

FIG. 14 is a rear view of the fender design of FIG. 8.
